W. P. Tracy, ATTORNEY

UNITED STATES PATENT OFFICE.

EDWARD NELSON, OF JERSEY CITY, NEW JERSEY.

NOZZLE FOR HOSE.

No. 927,376.

Specification of Letters Patent.

Patented July 6, 1909.

Application filed June 19, 1908. Serial No. 429,267.

To all whom it may concern:

Be it known that I, EDWARD NELSON, a citizen of the United States, residing at Jersey City, county of Hudson, and State of New Jersey, have invented a certain new and useful Improvement in Nozzles for Hose, of which the following is a specification.

My invention relates to a new and useful improvement in nozzles for hose, and has for its object to provide an exceedingly simple and effective device of this character whereby the water may be turned off at the nozzle, thus saving the person using the hose from running into the house or building to turn off the water each time it is so desired, as in the case of a person wanting a bucketful at a time.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a side elevation of my improved nozzle. Fig. 2, a longitudinal section thereof. Fig. 3, an end view thereof. Fig. 4, a side elevation of the parts of the valve, part of it being broken away to show the threaded opening therein. Fig. 5, a slightly modified form of valve stem, and, Fig. 6, a section at the line X—X of Fig. 2 looking in the direction of the arrow, the valve being removed.

In carrying out my invention as here embodied, A represents the casing of the nozzle which is preferably made from a single casting having a central barrel or bore B, this barrel being circular in cross section as clearly shown in Fig. 6. A portion of this casing is enlarged, as indicated by B', in which the valve to be hereinafter described is adapted to be situated, and below this enlarged portion, on the inside of the casing A, is formed the bridge C having the opening D, through which the lower portion of the valve is adapted to slide.

E indicates a lug formed on the outside of the casing, in proximity to its upper end, in which is formed the hole F for the reception of the bolt.

G represents a guide threaded into the upper end of the casing, having a slot H formed

therein, and upon this is placed the sliding member I, to which is secured the valve stem J, the upper end of which is curved to form the extension K, on which is cut a thread, so that when this extension K is passed through the sliding member I, a nut may be threaded thereon, holding it securely to said sliding member. The lower end of this valve stem is flared, as indicated by L, and has the threaded projection M which passes through the rubber washer N, and is then threaded into the lower member O of the valve, which has a guide stem P and a flared upper portion Q, the guide P being adapted to slide up and down within the opening D formed in the bridge C.

R represents a spiral spring which passes around the guide P, one end resting against the flared portion Q, the other end against the bridge C, thus normally holding the valve against its seat formed by the lower end of the guide G, when it is threaded in the casing A.

S indicates a lever secured to the lug E by the bolt T, on which is threaded the nut U for holding it in place. Pivoted to this lever is one end of the link V, the other end being pivoted to the sliding member I, so that when the lever S is pulled downward, it will slide the sliding member I downward which will open the valve, and in order that this may be held open any desired length of time, I provide a hook W on the end of the lever S, over which is adapted to pass the link Y which is fastened to the enlarged portion of the casing.

Z represents a perforated cap, which may be secured to the top of the sliding member I, so that as the water passes out of the nozzle, it will do so in the form of a spray.

In Fig. 5 I have shown a slightly modified form for attaching the valve to the sliding member, in which a thread J' is formed on the upper end of the valve stem J and this is threaded into a suitable opening K' formed in the screw K², before said screw K² has been threaded into the sliding member I.

In practice my nozzle is placed upon the end of a hose, where it is to be used, in such a place as the front of a house, in hot-houses, or for washing vehicles or at different points along a temporary supply pipe, such as are used in building operations. To open the nozzle so that water may be had, the lever S is pulled which will cause the sliding member I to slide around the guide G, which will

move the valve stem J in the same direction against the pressure of the spring R, thus opening the valve, allowing the water to flow out through the outer end, and if it is desired 5 to keep the valve open without holding it with the hands, the link Y may be placed over the hook W on the lever S, which will hold the valve open, and when this link Y is removed, the spring R will press the valve 10 against its seat and shut off the flow of water.

Of course I do not wish to be limited to the exact details of construction here shown, as these may be varied within certain limits without departing from the spirit of my invention.

Having thus fully described my invention what I claim as new and useful is—

1. As a new article of manufacture a self closing nozzle consisting of a casing, a portion 20 of which is enlarged, a bridge having an opening, formed in said casing at the lower end of the enlarged portion, a lug having an opening formed therein, formed on the outer surface of the casing in proximity to its upper end, a guide, having a slot formed therein, threaded in the upper end of the casing, a sliding member adapted to slide up and down on the outside of the guide, a valve stem so curved as to form an extension the 30 outer end of which is threaded, said extension adapted to pass through the sliding member, a nut threaded thereon for holding the valve stem in place, the lower end of said valve stem being flared, and having a threaded member secured thereto, a washer passing over said threaded member, a lower valve member having a circular guide portion and a flared portion adapted to be threaded upon the threaded member, thus holding the 35 washer in place, said circular guide portion adapted to slide within the opening formed in the bridge, a spiral spring placed about said guide portion resting against the flared portion and the bridge for normally holding 40 the washer against the valve seat, a perforated cap, means for detachably securing said cap to the outer end of the sliding member, a lever, a bolt for securing said lever to

the lug formed on the casing, a nut threaded on said bolt for holding it in place, a link connecting said lever with the sliding member, a hook formed on the outer end of the lever, and a link secured to the enlarged portion of the casing, adapted to pass over the hook, as 50 shown and described.

2. In a nozzle of the character described, a casing having an enlarged portion, a bridge formed on the inside of the casing below the enlarged portion thereof, a guide threaded into said casing, the lower end of which forms the valve seat, said guide having a slot cut therein, a sliding member adapted to slide upon the guide, a valve, the stem of which is secured to the sliding member, means for normally keeping said valve 65 closed, a lever, means for securing said lever to the casing, a link, one end of which is attached to the lever, the other end being fastened to the sliding member, and means for holding the lever down, thus holding the 70 valve open, substantially, as shown and described.

3. In a nozzle for hose, a casing, a portion of which is enlarged, a bridge having an 75 opening, formed in said casing at the lower end of the enlarged portion, a guide having a slot formed therein threaded in the upper end of the casing, a sliding member adapted to slide up and down on the outside of the guide, a valve stem one end of which is secured to the sliding member, the opposite end being flared, a lower valve member having a flared portion secured to the flared portion of the valve stem, a spiral spring adapted to continually press the flared portion against the 80 end of the guide, and means for holding the flared portion away from the end of the guide when so desired.

In testimony whereof, I have hereunto affixed my signature in the presence of two 90 subscribing witnesses.

EDWARD NELSON.
